UNITED STATES PATENT OFFICE

FREDERICK C. RUPPEL, OF GRAND RAPIDS, MICHIGAN, ASSIGNOR TO W. B. JARVIS COMPANY, OF GRAND RAPIDS, MICHIGAN

RADIATOR FOR MOTOR VEHICLES

Application filed March 10, 1928. Serial No. 260,757.

The main objects of this invention are:

First, to provide an improved radiator for automobiles and the like with a filling opening and closure in which the filling opening is readily accessible, and at the same time a structure which is compact, and novel and attractive in appearance.

Second, to provide a structure of this class in which various ornamental features may be readily embodied and also is well adapted to display the name plate or other emblem of the vehicle.

Objects pertaining to details and economies of my invention will definitely appear from the description to follow. The invention is defined in the claims.

A structure embodying the features of my invention is clearly illustrated in the accompanying drawings, in which:

20 Fig. 1 is a front perspective view of a structure embodying the features of my invention, the radiator being indicated by dotted lines,

Fig. 2 is a detail vertical central section on a line corresponding to line 2—2 of Fig. 1.

25 Fig. 3 is a detail vertical section corresponding to that of Fig. 2 of a modified form of my invention.

Fig. 4 is a detail vertical section showing another modification of my invention.

30 Fig. 5 is a detail section showing a further modification in the structure and illustrating the adaptability thereof to different ornate- 50 ments.

Referring to the drawings, 1 represents a 35 radiator and 2 the shell thereof. The radiator shell is provided with an opening 3 in the top thereof through which the filling neck 4 of the radiator projects, this neck being externally threaded in the embodiments illus- 70 trated.

The cap plate 5 has an opening 6 therein to receive the radiator neck, the plate being flat and resting upon the top of the shell. The annular nut 7 threaded upon the neck clamps the plate in position. The cap 8 is internally chambered to enclose this retaining nut and has an internally threaded flange 9 engaging the neck above the retaining nut. This cap closes against the top of the cap plate.

50 The cap plate in the embodiment shown in

Figs. 1 to 4, inclusive, has a depending portion 10 overlapping the front of the radiator shell and is provided with a name-plate space 11.

In the embodiment shown in Figs. 1 to 4 an ornamental projection 12 is provided above the name-plate. 55

In the embodiment shown in Fig. 3 the retaining nut 7 is omitted and the cap plate is retained by a stud screw 13 arranged through the front of the radiator shell and provided with a nut 14. 60

In the embodiment shown in Fig. 4 the cap plate 15 is provided with integral lugs 16 arranged through holes 17 in the top of the shell and offset or riveted therein. 65

In the embodiment shown in Fig. 5 the cap plate 18 has a winged ornament 19 at the front end thereof. 70

My improvements are well adapted for embodiment in various designs. The cap plate reinforces the radiator shell around the opening therein through which the filler neck projects so that the cap may be screwed down upon the shell. It also serves as a supporting means for the name plate, emblem or trademark of the vehicle. 75

I have not attempted to illustrate or describe various other modifications or adaptations which are possible as it is believed that the disclosure made will enable those skilled in the art to embody or adapt my improvements as desired. 80

Having thus described my invention what I claim as new and desire to secure by Letters Patent is:

1. The combination with a radiator shell having an opening in the top thereof, a radiator disposed within said shell and having a threaded filling neck projecting through said opening therein, a flat cap plate mounted on said shell and having an opening therein fitting said neck, said cap plate having an integral name plate member depending from its front edge and overlapping the front of the shell, a retaining nut threaded upon said neck to clamp said cap plate upon said shell, and a chambered cap threaded upon said neck above said retaining nut to enclose the same and with its lower edge closing against said cap plate. 85 90 95 100

2. The combination with a radiator shell having an opening in the top thereof, a radiator disposed within said shell and having a threaded filling neck projecting through said opening therein, a flat cap plate mounted on said shell and having an opening therein fitting said neck, a retaining nut threaded upon said neck to clamp said cap plate upon said shell, and a chambered cap threaded upon said neck above said retaining nut to enclose the same and with its lower edge closing against said cap plate.

3. The combination with a radiator shell having an opening in the top thereof, a radiator disposed within said shell and having a filling neck projecting through said opening therein, a cap plate mounted on said shell and having an opening therein through which said neck projects, said cap plate having a depending portion overlapping the front of said shell, means for retaining said cap plate, and a closure for said neck disposed above said cap plate.

4. The combination with a radiator shell having an opening in the top thereof, a radiator disposed within said shell and having a filling neck projecting through said opening therein, a cap plate mounted on said shell and having an opening therein through which said neck projects, said cap plate having a depending portion overlapping the front of said shell, and a closure for said neck disposed above said cap plate.

5. The combination with a radiator shell having an opening in the top thereof, of a radiator disposed within said shell and having a filling neck projecting through said opening, a cap plate mounted on said shell and having an opening therein through which said neck projects, means on said neck for retaining said cap plate, and a cap detachably mounted on said neck above said cap plate retaining means and removable independently thereof.

45 In witness whereof I have hereunto set my hand.

FREDERICK C. RUPPEL.
